FIG. 8

FIG. 1 is a left side elevational view of a mobile artillery toy showing the new design, the two turrets being adjusted so that the cannons they carry face toward the front of the vehicle, and the long narrow barrel being located in its inoperative rest position;

FIG. 2 is a right side elevational view of the toy;

FIG. 3 is a top plan view of the toy;

FIG. 4 is a front elevational view of the toy;

FIG. 5 is a rear elevational view of the toy;

FIG. 6 is a bottom plan view of the toy;

FIG. 7 is a top plan view of the toy, each of the turrets having been rotated 90° from the position shown in FIGS. 1-6, and the long narrow barrel being located in its operative position within the short wide barrel; and

FIG. 8 is a left side elevational view of the toy with the parts in the position shown in FIG. 7.

The broken lines indicating missiles are for illustrative purposes only.

I claim:

The ornamental design for a mobile artillery toy, substantially as shown and described.
